UNITED STATES PATENT OFFICE.

ALMON G. ALBRO, OF CORRY, PENNSYLVANIA.

HORSESHOE.

No. 821,973.

Specification of Letters Patent.

Patented May 29, 1906.

Application filed February 21, 1906. Serial No. 302,223.

To all whom it may concern:

Be it known that I, ALMON G. ALBRO, a citizen of the United States, residing at Corry, in the county of Erie and State of Pennsylvania, have invented new and useful Improvements in Horseshoes, of which the following is a specification.

My invention pertains to horseshoes of the removable-calk type; and it contemplates the provision of a horseshoe embodying simple and efficient means which may be depended on to preclude casual movement and displacement of a calk while the shoe is in use and yet is adapted to permit of the calk being quickly and easily removed and replaced with a new calk when necessity demands.

With the foregoing in mind the invention will be fully understood from the following description and claim when taken in connection with the accompanying drawings, forming part of this specification, in which—

Figure 1 is an inverted plan view of the horseshoe constituting the present and preferred embodiment of my invention. Fig. 2 is a longitudinal section of the same, taken in the plane indicated by the line 2 2 of Fig. 1 and showing the manner in which the toe-calk is secured in its holder. Fig. 3 is an enlarged detail section taken in the plane indicated by the line 3 3 of Fig. 1 and illustrating the manner in which the heel-calks are secured in their holders, and Fig. 4 is an enlarged perspective view of the toe-calk as the same appears when removed from the body of the shoe.

Similar letters designate corresponding parts in all of the views of the drawings, referring to which—

A is the body of my novel horseshoe. The said body is of the usual configuration and is preferably, though not necessarily, provided with the usual nail-holes a. It is also provided with an integral holder B for a toe-calk and integral holders C for heel-calks. These calk-holders are each provided with longitudinal grooves b, which are of dovetail form in cross-section and are open at their opposite ends, as shown in Fig. 1. Each calk-holder is further provided in the under portion of one side wall of its groove b with an indentation D, the inner wall E of which protrudes into the groove b and is designed to serve an important function hereinafter pointed out in detail.

F is the toe-calk of the shoe, and G G are the heel-calks. These calks F and G are of

dovetail form in cross-section to permit of their being moved endwise into and out of the grooves b in their respective holders, and each is provided in one of its sides with a depression, preferably in the form of a vertical groove H, as shown, designed to receive the protruding inner wall E of the indentation D in its respective holder, as clearly shown in Figs. 2 and 3.

In the practical use of my novel horseshoe the body A is formed with a shallow indentation D in one wall of each of the holders B and C, and the toe and heel calks are moved endwise into the grooves of their respective holders until they rest in the relative positions shown in Fig. 1. Then when the groove H of each calk is opposite the indentation D of the calk-holder complementary to the calk a punching implement is placed in the indentation and struck one or more blows with a hammer or the like, when, as will be readily apparent, the inner wall E of the indentation D will be caused to enter and rest in the groove H of the calk and in that way effectually prevent casual endwise movement or displacement of the calk. It will be noticed, however, that when the end of the calk is struck one or more blows with a hammer or the like the said protruding wall E of the indentation D will give outwardly, and thereby permit of the endwise movement of the calk out of its holder and the placing of a new calk in the holder. After the placing of the new calk the punching implement is placed in the indentation D and struck one or more blows in order to position the wall E of the indentation in the groove H of the new calk. From this it will be gathered that the inner wall E of the indentation in combination with the groove in the calk will effectually prevent accidental movement or displacement of the calk and yet will not interfere with the removal of the calk when the same is worn and the placing and fastening of a new calk in the holder.

It will be observed that the vertical groove H, extending throughout the height of each calk, serves by showing below the calk-holder to enable the party practicing my invention to readily position the upper portion of the groove to receive the inner wall of the indentation in the calk-holder.

An important feature of my invention consists in the utilization of a part of the body A to fasten each calk—i. e., the fastening of the calk without the employment of an ex-

traneous device such as is liable to casually work loose and in that way release the calk while the shoe is in use.

I have specifically described the construction and relative arrangement of the parts embraced in the present and preferred embodiment of my invention in order to impart a definite understanding of the said embodiment. I do not desire, however, to be understood as confining myself to the said specific construction and relative arrangement of parts, as such changes or modifications may obviously be made in practice as fairly fall within the scope of my invention as claimed.

Having described my invention, what I claim, and desire to secure by Letters Patent, is—

In a horseshoe, a calk of dovetail form in cross-section having a vertical groove H in one of its sides extending throughout its height, in combination with a calk-holder having a groove of dovetail form in cross-section in its under side into which the calk is introduced endwise and also having an indentation in the under portion of one of the side walls of the groove; the inner wall of the said indentation protruding into the groove of the holder and resting in the vertical groove of the calk.

ALMON G. ALBRO.

In presence of—
M. W. SMITH,
V. L. POWERS.
